APRON

Frank Collins, Dearborn, Mich.

Application May 22, 1948, Serial No. 28,659

4 Claims. (Cl. 2—50)

1 The present invention relates to an improved apron which is particularly but not exclusively adapted to be worn by patrons of hairdressing establishments or beauty parlors for the protection of clothing against accidental splashings or hairdressing fluids.

In hairdressing treatments, particularly in washing or dyeing the hair, or in shampooing, or the setting of permanent waves, or like operations on a patron seated in a hairdressing establishment or beauty parlor, it is difficult to avoid the accidental splashing of hairdressing fluids. In order to protect the patron's clothing from such splashings, it is common to drape a protective apron over the shoulders and the upper body portion of the seated patron. However, if the apron is of absorbent material, the hairdressing fluids are apt to soak through the apron and stain the clothing beneath. If the absorbent material is sufficiently thick to prevent soaking through, it becomes too heavy to be worn with comfort and serves as a blanket which overheats the patron.

On the other hand, if the apron is of material which is impervious to the hairdressing fluids, the latter tends to collect in the folds or creases of the apron on the patron's lap, for example, and eventually run off the edges of the apron onto the patron's clothing. In such instances, a towel or other absorbent material may be frequently applied to absorb the excess dressing fluids which fall onto the impervious apron. However, such a procedure is unsatisfactory, since it interferes with and delays the hairdressing operation. The procedure is also inefficient as a protective measure since the clothing is frequently spotted by hairdressing fluid dripping off the edges of the apron regardless of normal precautions.

A primary object of the present invention is to provide an improved apron for use in hairdressing establishments or beauty parlors and which provides a simple, effective and economical means for protecting the clothing of a patron from accidental drippings or splashings of hairdressing fluid.

Another object of the present invention is to provide an apron of the character described which provides a body portion of flexible sheet material which is impervious to hairdressing fluids and which is adapted to drape protectively over the shoulders and body of the patron, and which provides a plurality of strips of absorbent material on its outer surface so as to absorb drippings or splashings of hairdressing fluid which

fall on the impervious sheet and flow toward the peripheral edges thereof, the strips being detachable if desired to permit washing.

Another object of the present invention is to provide such an apron which adequately protects the clothing of the patron, yet which is light in weight and may be worn indoors with comfort without overheating the patron.

Other objects of this invention will appear in the following description and appended claims, reference being had to the accompanying drawings forming a part of this specification wherein like reference characters designate corresponding parts in the several views.

15 In the drawings:

Fig. 1 is a plan view of an apron embodying the present invention.

Fig. 2 is a plan view of another embodiment of an apron embodying the present invention.

20 Before explaining the present invention in detail, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

25 The apron shown in Fig. 1 by way of example of the present invention comprises a body protector member 10 of flexible sheet material, having the curved neck receiving recess 12 in its upper edge and the pair of lateral shoulder and back protecting wings 14 extending laterally and rearward from the edges of the neck receiving recess 12. Tie strings 16 likewise extend from the lateral edges of the neck receiving recess 12 to permit the apron to be drawn snugly around the neck of a patron seated for a hair treatment, with the wings 14 covering the shoulders and back portion of the patron.

30 The sheet body portion of the apron, including the protector members 10 and 14, are preferably fabricated from lightweight sheet material which is impervious to hairdressing fluids and dyes, as for example a transparent, lightweight, flexible sheet vinylite plastic, which may be comfortably worn by the patron without causing undue warmth. The transparent material is preferred in most instances since it permits the patron's body heat to be readily radiated. Thus the patron may rest in comfort during the hair treatment. However, sheeting of other fluidproof materials may be employed where desired.

In order to absorb accidental splashings of dyes or other hairdressing fluids falling on the impervious sheet portions 10 or 14, as the splashings flow by gravity toward the lower edges of the apron, the present invention provides the flexible guard strip of absorbent material 18 transverse to the body portion 10 and the similar absorbent guard strips 20 transverse to the lateral wings 14. One or more supplemental absorbent strips parallel with the strips 18 and 20 may be employed if desired. The strips 18, 20 preferably run essentially horizontally or transverse to the longitudinal axis of the apron when the latter is worn by the seated patron so as to provide adequate protection against the possibility of fluid dripping from the edges of the impervious sheet material 10 and 14 onto the clothing of the patron.

A modified form of the apron is shown in Fig. 2 and comprises the impervious body portion 10A, the neck recess 12A, the impervious lateral wings 14A, and draw strings 16A, essentially as previously described. In this instance, the strips of absorbent material 18A and 20A complete an essentially continuous absorbent strip around the neck recess 12A. Hairdressing fluid accidentally splashed on the apron will meet and be absorbed by one of the absorbent strips 18A or 20A as it flows toward the lateral edges of the apron. In this instance, portions of the strips 18A and 20A run along the peripheral edges of the apron, being spaced slightly inwardly therefrom so as to prevent contact with the patron's clothing and staining of the latter in the event that the strips 18A or 20A should become saturated.

As described above, supplemental absorbent strips essentially parallel to those shown may be employed if desired. However, in the ordinary situation, the splashing of dye or hairdressing fluid onto the apron is relatively light and occurs at the upper portion thereof around the shoulders and breast of the patron. It is accordingly not essential that the transverse strips 18 and 18A shown in Figs. 1 and 2 be disposed near the lower edges of the apron in the ordinary situation.

In the present instance, the strips 18A and 20A are detachably secured to the sheet material 10A and 14A by a plurality of snaps 22 to permit removal for cleaning.

However, the strips may be permanently secured to the impervious apron material if desired. By the construction shown, it is apparent that a lightweight protective apron has been provided which is both impervious to hair dressing fluid and which also permits means for absorbing fluid splashing onto the apron before the fluid can flow onto the clothing of the patron.

By employing the absorbent material in strips, adequate absorption protection is provided with a minimum of material and weight, minimizing the cost of the material required and providing a lightweight apron which may be worn comfortably by the patron without overheating.

Having thus described my invention, I claim:

1. An apron adapted to protect the clothing of a patron in a hairdressing establishment and comprising a fluidproof body protector of flexible sheet material adapted to cover the shoulders and upper body of the patron, and means to catch accidental splashings of hairdressing fluid on said body protector and including guard strips of absorbent material secured to said body protector and extending transversely from one side to the other side thereof.

2. An apron as claimed in claim 1 and being further characterized in that said guard strips are detachably secured to said body protector.

3. In an apron for protecting the clothing of a patron in a hairdressing establishment from accidental splashings of hair dressing fluid, the combination of a body protector of flexible sheet material impervious to hairdressing fluids and adapted to cover the upper anterior body portion of said patron, a neck receiving recess in the upper edge of said body protector, shoulder protecting wings on said body protector and extending laterally and rearwardly from the lateral portions of said neck receiving recess to overlie the shoulders and back portion of said patron, and guard means to absorb splashings of hairdressing fluids on said impervious body protector sheet and including strips of flexible absorbent material secured to said body protector and the lateral wings thereof.

4. The combination as claimed in claim 4 and being further characterized in that said guard strips are detachably secured to said impervious sheet material and extend generally transverse to the gravity flow of fluid thereon when said apron is protectively draped over the shoulders of said patron.

FRANK COLLINS.
